UNITED STATES PATENT OFFICE.

BARKER LISTER, OF SAVANNA, ILLINOIS.

TUYERE-IRON.

SPECIFICATION forming part of Letters Patent No. 372,659, dated November 8, 1887.

Application filed December 18, 1886. Serial No. 222,016. (No model.)

To all whom it may concern:

Be it known that I, BARKER LISTER, a citizen of the United States, residing at Savanna, in the county of Carroll and State of Illinois, 5 have invented certain new and useful Improvements in Tuyere-Irons; and I do hereby declare the following to be a full, clear, and exact description of the invention, such as will enable others skilled in the art to which it applies to make and use the same, reference being had to the accompanying drawings, which form part of this specification.

My invention relates to an improvement in that class of tuyeres in which air is forced into 15 and through an air-chamber underneath the fire, and has for its object to provide means for directing the blast under all portions of the fire at the same time without permitting the melted metal to fall below into the chamber, and also an adjustable cup and valve by 20 which the blast can be entirely shut off from the fire at will and the chamber cleared of cinders by the blast of the bellows; and it consists in the construction hereinafter described, 25 and more particularly pointed out in the claims.

Referring to the drawings, Figure 1 is a perspective view of my tuyere. Fig. 2 is a part 30 sectional vertical view on the line $z z$ of Fig. 1, showing the position of the interior parts of my device when the fire-valve is closed. Fig. 3 is a cross-sectional view on the line $x x$ of Fig. 2, showing the guide-bar. Fig. 4 is an enlarged view of the blast-valve. Fig. 5 is an 35 enlarged view of the internal adjustable valve for closing or opening a tube in the lower part of the chamber, said valve being shown raised to open the tube.

Like letters of reference refer to corresponding 40 parts in each figure of the drawings.

A represents a cylindrical casing having an enlarged top, B, with a concavo-convex central portion provided with an opening communicating with the air-chamber below. The 45 lower end of the cylinder is enlarged at a , to give additional strength to the walls, and within the lower end there is fitted a flanged bottom, C, which projects upward within and underneath to the periphery of the enlarged 50 portion.

In the center of the flanged bottom there is

provided a hole, c , in which a vertical rod, D, is placed, extending upward to the top B.

On the upper end of the rod D there is secured an adjustable concavo-convex valve, E, 55 the upper side of which is concave. This valve is provided with inclined holes e near its thin edges, extending downward and outward, communicating with the air-chamber below to enable the current of air-blast to in 60 part pass under and up through the bed of coals on the valve or cup E, while that forced over the sides will strike the sides of the fire. These holes are at a sufficient distance from the center of the upper concaved surface of the 65 valve to avoid the liability of the melted iron passing through them to the chamber below. As the valve is raised it closes the central opening, b , of the top, and its thin edges are so extended as to fit well up on the convex under 70 side of the top and bring the upper side of the perforations or holes e in the valve against the under side of the top, forming a practically air-tight joint between the opening b and the air-chamber below.

At about midway of the height of the cylinder a guide or centering bar, F, extends across the air-chamber, and is secured to its sides by screws or other suitable means. Through the enlarged center portion, f , of this 80 bar the vertical rod D passes, and by means of the bar is held in a central position when being moved up and down, and also the upper side of the bar serves as a rest for the valve E when it is depressed or let down from the top. 85

In one side of the cylinder there is provided an opening about midway of its height for a blast-pipe, G, which communicates with the blowers or bellows for forcing air into the chamber. A valve-tube, H, extends from the 90 upper side of this pipe, opening into it, in which there is a valve, h . The upper portion of this valve consists of a rod which fits closely into and fills the tube H, causing a sufficient degree of friction, when turned, to hold the 95 valve in position, while its lower part constitutes a thin blade adapted to be turned in the blast-pipe to open or close the draft to regulate the current of air in the chamber and upon the fire in the concave top B.

Within one side of the bottom, and through the enlarged lower end of the cylinder, there

is a tube, I, inclined downward and outward, through which the accumulated dust, cinders, or melted iron is expelled.

A lever-arm, J, is loosely pivoted to the 5 vertical rod D within the air-chamber at a suitable distance above the bottom C. This arm J has a pivotal bearing on a post, j, fastened to the bottom. Its extended bent portion i is pivotally connected with a second lever-arm, K, which also has a pivotal bearing in a post, k, secured to the bottom C. The lever-arm K is extended outward and downward from the post, and has a valve, L, secured to its lower end, which fits into or covers 15 the inner end of the tube I, so that when the rod D is raised the valve E closes the central opening, b, of the top, the same action of the rod raising the valve L from the inner end of the tube I, leaving a clear communication 20 outward through this tube at the bottom of the air-chamber to enable the dust and cinders to be blown out by forcing an air-blast into the chamber and out through this tube without disturbing the fire.

25 The vertical rod D may be raised and lowered by any suitable means desired—as a foot-lever, d, pivoted in one side of the lower end of the cylinder and extending outside the forge at a convenient point for the foot of the operator, and adapted to be held in any desired 30 position by any well-known means—as by a side ratchet—or the rod may be raised by wedges and held in a fixed position when frequent changes for blowing out the foreign matter in 35 the chamber are not found necessary.

In operation, when the valve E is lowered and the tube I is closed, the blast of air is forced into the air-chamber through the pipes G, the strength of the current being regulated 40 by the valve h, and passes over the edges and through the openings in valve E to the fire on the upper side of the valve and within the inclined cover or top B.

When it is desired to clean the air-chamber 45 of any accumulation of dust or cinders, the rod D is raised, closing the opening b of the top and opening the tube I in the bottom, when a strong blast from the bellows or wind-wheel is forced into the air-chamber, creating 50 an eddy, and out through the tube I, carrying with it all foreign matter that may have accumulated therein.

I am aware that it is not new to form a 55 tuyere-casing having a central rod with a perforated valve to partially close the opening in the top; also a blast-pipe in the side of the casing having a valve; also a grate in an air-chamber for the passage of cinders and dust and to support the end of the blast-pipe; also 60 a valve rod reduced in diameter and its lower portion, so that when raised it leaves an opening in the bottom around the rod, and I do not, therefore, claim these broadly.

Having fully described my invention, what I claim as new, and desire to secure by Letters 65 Patent of the United States, is—

1. A forge-tuyere iron consisting of a cylinder having a concavo-convex top and a removable flanged bottom projecting upward within the cylinder, and underneath to the 70 periphery of the enlarged lower end of the cylinder, said bottom having a central vertical rod extending through a guide-bar across the air-chamber and provided with a valve adapted to fit the convex under side of the 75 top and close the opening therein, as and for the purpose set forth.

2. In a forge, the combination, with a cylinder having a concavo-convex valve therein provided with inclined holes near its thin 80 edge, the valve being adapted to close an opening in the top substantially air-tight by the adjustment of a rod underneath, of a blast-pipe in one side of the air-chamber having a tube opening into the pipe, said tube being provided with a friction-rod to hold the valve in position in the pipe to regulate the current of air to the chamber, as and for the purpose set forth.

3. The combination, with a tuyere-casing 90 having a valve adapted to fit the convex under side of the top and close an opening therein by adjustment on a vertical rod through the bottom of the chamber and a guide-bar, of a valve connected with the rod for opening the waste-pipe in one side of the bottom when the rod is 95 adjusted to close the opening in the top, as and for the purpose set forth.

4. The combination, with a tuyere-casing having a central rod through the bottom and a 100 guide-bar for adjusting a valve to close an opening in the top of the casing, of a lever-arm pivoted to the vertical valve-rod and to a second lever arm adapted to close a valve over the waste-pipe in one side of the bottom 105 when the vertical rod is adjusted to close the opening in the top, as and for the purpose set forth.

5. In a forge, the combination, with a casing, of a valve with inclined holes near its 110 edge, a vertical valve-rod, a guide-bar on the vertical rod, a blast-pipe in the side of the cylinder having a valve therein, and a waste-pipe passing through the bottom and side of the cylinder, and a lever-arm pivoted to the 115 vertical valve-rod having a pivoted bearing on a post in the bottom, with its opposite end pivoted to a second lever-arm having a valve attached to it for opening and closing the waste-pipe, as and for the purpose set forth.

In testimony whereof I affix my signature in presence of two witnesses.

BARKER LISTER.
